UNITED STATES PATENT OFFICE.

PER ADOLF PETERSON, OF NEW YORK, N. Y.

SALT-CELLAR.

No. 888,652.

Specification of Letters Patent. Patented May 26, 1908.

Application filed September 6, 1905. Serial No. 277,235.

To all whom it may concern:

Be it known that I, PER ADOLF PETERSON, a citizen of the United States, residing at 229 East Fortieth street, New York city, in the county of New York and State of New York, have invented new and useful Improvements in Salt-Cellars, of which the following is a specification.

This invention relates to salt-cellars such as are provided with means for stirring the salt to prevent the cellar from becoming clogged.

The principal object of the invention is to improve the construction of such devices; furthermore, to increase their efficiency in operation.

With the foregoing and other objects in view which will appear as the description proceeds, the invention resides in the combination and arrangement of parts and in the details of construction hereinafter described and claimed as a practical embodiment thereof.

In the accompanying drawing forming part of this specification; Figure 1 is a vertical central section through a salt cellar constructed in accordance with the invention. Fig. 2 is a side elevation of the stirring mechanism removed from the salt cellar. Fig. 3 is a plan view of the stirring mechanism. Fig. 4 is a side elevation, partly in section of a slightly modified construction. Fig. 5 is a plan view of the stirring mechanism.

Like reference numerals indicate corresponding parts in the different figures of the drawing.

The reference numeral 1 indicates a salt cellar made of any suitable size, shape and construction.

The reference numeral 2 indicates the removable cap which is perforated in the usual manner.

The salt cellar 1 is provided with a stirring blade 3 which is adapted to be rotated by any suitable mechanism, preferably as hereinafter described. The blade 3 is slotted or incised from its opposite edges as indicated at 4, 5, 6, 7 and 8, and is then drawn out so as to assume a zig-zag shape.

While the blade 3 may be rotated in any suitable manner, said blade preferably is provided with a bevel gear 9 which is secured in any suitable manner to the upper end there-

of and is journaled by means of a pin 10, or other suitable device upon a framework 11 having radiating arms 12, 13, 14 and 15 which are adapted to fit into suitable downwardly extending slots in the upper end of the salt cellar 1, said arms being held within the slots by means of the cover 2. The radiating arm 15, as shown in Fig. 2, is bent downward to form a journal for a shaft 16 on which is mounted a small bevel gear 17, meshing with the gear 9. At its outer end the shaft 16 is provided with a finger piece 18 by means of which said shaft can be rotated to impart motion to the blade 3 through the gears 17 and 9.

Secured in any suitable manner to the pin 10, above the framework 11, is a blade 19 which is suitably notched along its upper edge as indicated at 20. The blade 19 is formed with a slot into which is fitted a transversely scraping blade 21, the upper edge of which is disposed above the upper edge of the blade 19. It will be understood that the blades 3, 19 and 21 are simultaneously rotated by means of the finger piece 18. By disposing the upper edge of the scraping blade 21 slightly above the upper edge of the blade 19, it is found in practice that any salt which may adhere to the cover 2 is readily removed.

The blade 19 is designed primarily to prevent collection of material in the lid of the salt cellar to such an extent as to interfere with the proper scraping operation of the blade 21, it being obvious that in the initial movement of the blades, the blade 19 will tend to cut the material collected below the operative edge of said blade 21, hence facilitating the proper scraping of the material and directing the same back into the salt cellar in a fine condition rather than in the lumping condition which would result from the operation of blade 21 alone if a considerable quantity of material had been collected.

The construction illustrated in Figs. 4 and 5 is practically the same in all essential respects as that illustrated in Figs. 1 and 2, except that the operating mechanism or gear 100 for rotating the blade 3, is inclosed in a casting 22 so as to prevent the same from becoming clogged or corroded by the salt.

Having thus described the invention what is claimed as new, is:

A salt cellar having a stirring blade, a

scraping blade connected with the upper end of the stirring blade, a second blade arranged transversely to the first mentioned scraping blade and having its upper edge disposed below the upper edge of the first mentioned scraping blade, and means for rotating the said blades.

In testimony whereof, I have affixed my signature in presence of two witnesses.

PER ADOLF PETERSON.
